(57) **CLAIM**

The ornamental design for a free-standing cup holder, as shown and described.

DESCRIPTION

FIG. 1 is a perspective view of a free-standing cup holder showing my new design.

FIG. 2 is a front elevational view thereof a back elevational view being identical to the front elevational view.

FIG. 3 is a side elevational view, a side elevational view from the opposite being identical thereto.

FIG. 4 is a top view thereof; and,

FIG. 5 is a bottom view thereof.

The broken lines are for illustrative purposes only and form no part of the claimed design.
